UNITED STATES PATENT OFFICE.

ROBERT BOOTH, OF LONDON, AND FREDERICK CROSLAND, OF EGREMONT, ENGLAND.

KILN.

SPECIFICATION forming part of Letters Patent No. 777,936, dated December 20, 1904.

Application filed July 22, 1904. Serial No. 217,615.

To all whom it may concern:

Be it known that we, ROBERT BOOTH, a resident of the city and county of London, and FREDERICK CROSLAND, of Egremont, in the county of Chester, England, subjects of the King of Great Britain and Ireland, have invented a certain new and useful Improvement in Kilns, (for which we have filed in Great Britain a provisional application for Letters Patent, No. 20,141 of 1903, on the 18th of September, 1903,) of which the following is a true and exact description, reference being had to the accompanying drawings, which form a part thereof.

15 Our invention relates to the construction of kilns for calcining lime and similar purposes, and has for its object to provide a kiln which will require a relatively small quantity of fuel, which will automatically cause a turning over of the pieces of limestone or other material being calcined as it descends through the shaft, and which will be cheaper to build and maintain than previous kilns having the same or similar modes of operation.

20 Our invention consists, broadly speaking, in forming the top and bottom portions of the kiln-shaft of elongated form in cross-section, the longer axes of the sections of the two portions lying crosswise to each other and preferably at right angles, and, further, of connecting their top and bottom portions by an intermediate section, a portion of which is approximately circular in section, while above and below said circular section the walls of the intermediate portion gradually conform to the shapes of the top and bottom portions of the kiln. By preference we form the top and bottom portions of the kiln with vertical walls, while of course the walls of the intermediate section converge from the narrower ends of the upper section to the sides of the lower section and diverge from the sides of the upper section to the ends of the lower section.

Reference being now had to the drawings, 45 which illustrate our invention as applied to a kiln heated by gas, Figure 1 is a vertical sectional elevation on the line 1 1 of Fig. 2; Fig. 2, a vertical sectional elevation on the line 2 2 of Fig. 1; Fig. 3, a cross-section on the line

33 of Fig. 1; Fig. 4, a cross-section on the line 50 44 of Fig. 1; Fig. 5, a cross-section on the line 55 55 of Fig. 1; Fig. 6, a cross-section on the line 66 of Fig. 1, and Fig. 7 a cross-section on the line 77 of Fig. 1.

A is the masonry of the kiln, of which the 55 vertical shaft is shown at B E D C, the upper portion B having an oval section with vertical walls, the lower section C being also of oval section with vertical walls, but having the longer axis of its oval set at right angles 60 to that of the upper portion B. The intermediate section has its walls E D symmetrically converged or diverged, so as to connect with the walls of the top and bottom portions, the sections varying from the ovals of the connected sections to an approximately circular section, as shown at D.

F indicates the gas-flue from a producer or other source of gas, said flue connecting, through branches G G, with a gas-flue H, 70 from which ports I I, &c., lead to the interior of the kiln, air being supplied as desired.

K is a feather to separate the burnt lime, and L L draw-holes for the lime.

It will be readily understood that the lime-stone in passing down through the shaft of the kiln is shifted and turned as the mass conforms to the varying section of the intermediate portion, and thus each stone is exposed to the ascending gases on all sides with great 80 increase of the rapidity and thoroughness of the calcining. It will also be obvious that our kiln is one which can be easily and cheaply built.

Having now described our invention, what 85 we claim as new, and desire to secure by Letters Patent, is—

1. A kiln for calcining lime or other material having a vertical shaft or passage, the top of which is in cross-section longer in one direction than in the opposite direction, said shaft having a bottom portion which is of similar shape to the top but with the longer axis of the elongated section extending cross-wise to that of the upper section, and said 90 shaft having an intermediate portion substantially circular in section at one point and gradually conforming above and below said circu-

lar zone to the shape of the top and bottom portions.

2. A kiln for calcining lime or other material, having top and bottom portions of elongated section and substantially vertical walls, an intermediate portion having a substantially circular section at one point and gradually conforming above and below said circular section to the elongated sections of the top and bottom portions.

3. A kiln for calcining lime or other material, having top and bottom portions of elongated section and substantially vertical walls, the longer axes of said top and bottom portions lying crosswise said shaft having also an

intermediate portion having a substantially circular section at one point and gradually conforming above and below said circular section to the elongated sections of the top and bottom portions.

ROBERT BOOTH.
